(57) **CLAIM**

The ornamental design for an electric battery as shown and described.

DESCRIPTION

1. Electric Battery

1.1 is a top plan view of an electric battery;

1.2 is a bottom plan view thereof;

1.3 is a right side elevation view thereof;

1.4 is a left side elevation view thereof;

1.5 is a front elevation view thereof;

1.6 is a back elevation view thereof; and

1.7 is a perspective view thereof.

The broken lines in the drawings illustrate portions of the electric battery that form no part of the claimed design.
